[57] **CLAIM**

The ornamental design for a photographic flash camera, substantially as shown and described.

DESCRIPTION

FIG. 1 is a perspective front view of a photographic flash camera embodying our novel design with the flash element in an inoperative position,

FIG. 2 is a front view thereof with the flash element in an elevated, operative position,

FIG. 3 is a front view thereof with the flash element in the inoperative position,

FIG. 4 is a rear view thereof,

FIG. 5 is a top-plan view thereof,

FIG. 6 is a bottom-plan view thereof,

FIG. 7 is a right-side view thereof, and

FIG. 8 is a left-side view thereof.
